UNITED STATES PATENT OFFICE

ERNEST B. PRIEBE, OF RICHMOND HILL, NEW YORK, AND DANIEL P. MINER, OF PROVIDENCE, RHODE ISLAND, ASSIGNEES, BY DIRECT AND MESNE ASSIGNMENTS, TO FURNACE ENGINEERING COMPANY, INC., OF NEW YORK, N. Y., A CORPORATION OF NEW YORK

FURNACE GRATE

Original application filed June 25, 1921, Serial No. 480,394. Divided and this application filed April 4, 1927. Serial No. 181,014.

This invention is a novel furnace grate adapted for use in connection with automatic stokers and being herein illustrated in connection with an underfeed stoker for a boiler furnace. The general objects of the present invention are to afford a furnace grate and stoker of greater efficiency in operation and superior strength and durability in construction. A particular object is to minimize the difficulty of the sifting of ashes through the grate into the wind box, which has been quite pronounced in certain types of stokers. Another object is to improve the operation and efficiency of the furnace by perfecting the manner and means of air distribution. Another specific object is to afford a novel and advantageous system of twyers for a furnace grate. Other and further advantages of the present invention will be made to appear in the hereinafter following description of one form of embodiment thereof or will be apparent to those skilled in the art.

To the accomplishment of the objects and advantages mentioned the present invention consists in the novel furnace grate and stoker herein described and illustrated and the novel features of arrangement, combination, construction and operation thereof.

In the accompanying drawings forming a part hereof Fig. 1 is a longitudinal section, taken on the line 1—1 of Fig. 2, of a furnace, stoker and grate embodying the principles of the present invention.

Fig. 2 is a transverse section taken on the line 2—2 of Fig. 1, looking toward the rear or bridge wall of the furnace.

Fig. 3 is a perspective view showing the construction and arrangement of the different kinds of members constituting the main grate.

Fig. 4 is a partial vertical section taken at or beneath the position of the line 4—4 appearing on Fig. 3.

This application is a division of our application for furnace grates, filed June 25, 1921, Serial No. 480,394, being based upon a portion of the original disclosure of said application, the same having now resulted in United States Patent No. 1,633,418, granted June

21, 1927 without containing the complete original disclosure.

Although the invention might be applied to furnaces, stokers and grates of various kinds and types we have merely shown the same applied to the kind of furnace embodying what is known in the trade as a "Type E" stoker. The so-called Type E stoker is used more especially for boilers of smaller sizes and usually there is but one retort to the furnace, although we wish it understood that the single retort shown in Figs. 1 and 2 could be duplicated, or a number of retorts maintained beneath a single boiler. Certain of the devices herein shown, including the stoker actuating mechanism in front of the furnace, are not herein claimed to be novel, but indeed are well known constructions not requiring detailed description; for example, the infeeding means for the coal, shown in Fig. 1, is substantially like that of well known Type E stoker mechanisms; the Type E stoker is exemplified in the patent of Wood No. 818,010 of April 17th, 1906.

Referring to the details of the herein illustrated embodiment of the present invention, the combustion chamber of the furnace is shown as bounded by the usual wall 7 at the front, bridge wall 8 at the rear and side walls 9, 9, and at the upper part of the combustion chamber is indicated a portion of a water tube boiler 10. The entire structure is shown resting upon concrete foundations 11 within which is provided, for each retort, an air duct 12 which serves to convey forced draft, controlled by damper 13, into the passage 14 constituting an air box directly beneath the retort and supplying air to the two opposite wind boxes beneath the grates, as will be described.

Above the grates is shown the fuel bed 15 and while the present invention might be applied to a furnace having a fuel bed maintained in different ways, for example, by overfeed, it is herein shown maintained by underfeed, as is customary with the illustrated type of grate. An exterior fuel hopper 16 delivers fuel directly in front of a reciprocating ram 17 which at each advance stroke thrusts a designated amount of fuel 100

into the lower part of the fuel bed in the furnace. The ram 17 is rigidly connected with a reciprocating crosshead 18 actuated through a connecting rod 19 by a piston 20 within a cylinder 21 supplied with steam by a pipe 22, the operation of these parts being regulated by mechanism 23, the details of which are well known and form no part of the present invention.

10 The fuel thrust into the furnace by the ram 17 passes through the expanding throat 24 into the retort 25. The fuel passes rearward through the length of the retort and also piles up and spills over laterally at both sides forming a symmetrical fuel bed, as shown in Fig. 2, the fuel traveling down the inclined grates at the two sides and finally, when burned out, being discharged by the dumping grates 26 into the ash pits 27. The 15 general course of the fuel having been thus explained the construction of the retort, the grates, the wind boxes and the air control will now be described.

20 The retort 25 has its bottom formed by a plate 29 which as usual in this type of furnace is arranged to reciprocate rearwardly and forwardly, the side edges of the plate 29 resting upon ribs 30 formed on the wind box walls. The retort bottom is shown as 25 provided with the usual pushers 31 which are inclined at their front sides and serve to assist the rearward travel of the fuel throughout the length of the retort. The reciprocation of the retort bottom is effected by its 30 forward extension 32 which is connected with the reciprocating crosshead 18 and forms the fuel support at and to the rear of the throat. The ram 17 is rigidly connected upon the plate 32 and thereby receives its reciprocation. The rear extremity of the bottom plate 29 slides beneath an inclined plate 33 forming 35 the rear end of the retort.

40 In this symmetrical design of furnace the retort stands between two similar grates which are air supplied and which, therefore, in effect form the upper sides of two opposite similar chambers or wind boxes. These will now be described. Owing to the preferred 45 flaring shape of the retort 25 each of the wind boxes may be considered as having a ridge or peak and two slopes, an abrupt slope from the ridge on the retort side, comprising twyer members, and a more gradual slope or incline at the outer side, constituting the 50 grate.

55 The inner side of each wind box is preferably a vertical metal wall, the lower part 35 of which forms a wall of the air box 14 and the upper part 36 of which forms a side wall 60 of the retort. Resting on the walls 36 are the sloping twyer members 37 consisting of upstanding members in face contact, with grooved edges affording tapered apertures discharging into the retort. Above these 65 twyer members rest a series of cap plates 38

which form the ridge or peak of the grate. At the other side of the cap plates extends at a downward slant the main grate 39 at each side. The lower end of the grates rest upon bearing plates 41 at the right and left. Below the bearing plates are downwardly extending walls 43, and therebelow diagonal walls 44 connecting with the bottom walls 45, which extend toward the center and are united with the first mentioned upright wall 70 portions 35 bounding the air box. 75

Each wind box is shown with a partition 46 separating it into two chambers connected by an opening controlled by a damper 47 operated by an external handle 48. Each wall portion 35 has a sliding damper 49 operable from an exterior handle 50 through a sliding rod 51. The course of the air is thus through the main air duct 12, the air box 14, the dampers 49 into the wind box and partially through the dampers 47 and upwardly from the wind box through all portions of the grate into the fuel bed. 80

85 The wind box construction is held steady and rigid by its support and attachment upon a portion of the concrete foundation 11. The upright wall 36 has attached to it two or more three-armed brackets 53. One arm of this bracket is used to secure in place the twyer members 37 by means of a rod 54 passing through the bracket arms and perforated extensions of the twyers. Similarly a second arm of the bracket is used to give support to the stationary bars of the grate 39 or 40, a rod 55 extending through the 90 arms and extensions of the bars. 95

95 The cap plates 38 are of novel form as seen in all the figures. Each cap plate is beveled at its front end, giving an inclined overhang 59 which fits against a corresponding incline of the adjacent cap plate as will be clear from Fig. 1. We prefer that the cap plate should be constructed with grooves 60 forming apertures at the undersides of the plates for delivering air laterally in both 100 directions, that is, into the retort and above the main grate. The cap plates are also shown provided with ribs 61 which are arranged longitudinally, these serving to divide the surface of the cap plates into concave 105 areas which we find to be of substantial advantage. An action takes place during combustion by which ashes become deposited and lie upon the iron of the cap plates in the depressions or concavities between the ribs. 110 This gives a decided protection against the deterioration of the plates and substantially prolongs the life of the cap plates. 115

120 The cap plates are shown locked and held in place by means of dovetail extensions, such as to fit between the inclined twyer members 37 and the upper edges of the stationary bars of the grates 39.

125 Coming now to the main grates, each of these comprises a series of inclined grate 130

bars arranged adjacent to each other extending at right angles to the length of the retorts and, of course, longitudinally to the downward advancing travel of the fuel, which passes laterally from the retort toward the dumping grates near the opposite side walls. These side by side grate bars are shown as stepped; that is each one of them is formed with a series of horizontal surfaces one beneath another so that the advancing fuel bed passes downwardly step by step toward the discharge. Alternate grate bars reciprocate longitudinally of the direction of the fuel feed relatively to the remaining bars which are preferably stationary or non-reciprocating. This construction is shown in front elevation in Fig. 2, which shows a stationary bar at the right side and a reciprocating one at the left. Fig. 3 shows several adjacent bars in perspective, partly broken away, and Fig. 4 is a vertical cross section of several of them. The alternate stationary grate bars 65 have the movable grate bars 75 between them and the two are of slightly different construction for a purpose which will appear. Each stationary grate bar has its topmost portion, which may be termed the top piece or top step 66, of the combined width of two adjacent grate bars. Thus the entire top of this system of grate bars consists of stationary members 65 and these are so shaped and arranged as to engage and lock with the dovetail of the cap pieces 38, already referred to.

The stationary grate bar 65, below its flat top step 66 is formed with integral second, third, etc. steps 67 to 72, a total of 7, at successively lower levels. The grate bar has a substantial vertical dimension below each step and this downward extension is provided with several horizontal ribs or tongues 73, extending to the right in Figs. 3 and 4, and 74 extending to the left, staggered or offset relatively to the ribs 73. These ribs and the recesses between them are for the purpose of engaging similar ribs and recesses on the reciprocating grate bars giving a compact interfitting system, sufficiently loose fitting, however, to permit the forced draft of air to pass horizontally between the grate bars for discharge into the fuel at each level of the grate.

Each of the movable grate bars 75 is formed with a top step 76. This is not at the same level with the top sections of the stationary bars, but is accommodated between the latter and the uppermost rib 73, as clearly shown in Figs. 3 and 4, the upper end of the movable bars thus receiving support and guidance for their reciprocating movements. The succeeding lower steps 77, 78, etc. of the movable grate bars are the same levels as the corresponding steps 67, 68, etc. of the stationary bars; and the depending portion below each step of the movable bar is

provided with ribs or flanges 83 and ribs 84 which partake in the interengaging structure and function already mentioned.

This construction of grate gives very effective air supply to the fuel bed and yet is such as to practically prevent the possibility of siftings passing into the wind boxes. The air outlets are horizontal and there would be no tendency for ashes, etc. to pass inwardly toward the air supply. At the same time the air supply is ample and is delivered in an effective direction and with thorough distribution beneath the entire area of the fuel bed.

The reciprocating or oscillating movements of the grate bars 75 are effected through a connecting rod 85 actuated by a rock arm 86 or a rock shaft 87 which is worked automatically under control of the timing mechanism 23.

The illustrated features of the present invention, involving a certain amount of looseness and play between the different grate bars, prevents any damage from expansion and contraction of the metal; the structure has an elasticity or self yielding quality which takes care of the difficulties frequently involved in the expansion of the metal. Another and very important advantage of this invention is the protection of the grate bars by maintaining them relatively cool. This is due to the mode of air travel, which passes horizontally through the spaces between the inclined grate bars and therefore has an extended length of travel in contact with the metal. The cooling effect is therefore applied more efficiently and completely than in a different arrangement, and the heat which is produced at the outer surface of the grate bars is the more readily conveyed away and dissipated, thus minimizing the burning away and destruction of the metal of the grate bars.

It will thus be seen that we have described a furnace grate embodying the principles and attaining the objects and advantages of the present invention. Since many matters of arrangement, combination, design and detail may be variously modified without departing from the principles involved, it is not intended to limit the invention to such matters except in so far as specified in the appended claims.

What is claimed is:

1. In a furnace having a central fuel retort and a pair of oppositely inclined grates one along each of the lateral sides of the retort, the retort discharging laterally over such sides upon such grates, each grate composed of inclined grate bars (65, 75) having stepped fuel supporting top sides, loosely interfitting to afford narrow air passages delivering into the fuel bed, and alternate grate bars (65) being stationary and having wide topmost portions alined longitudinally with

respect to the retort, the remaining bars (75) being movable and terminating short of such topmost portions, and connections for methodically reciprocating the movable bars.

- 5 2. In a furnace having a central fuel retort and a pair of oppositely inclined grates one along each of the lateral sides of the retort, the retort discharging laterally over such sides upon such grates, each grate composed of alternating inclined grate bars of two shapes each having fuel supporting steps, the grate bars of one shape having wide top portions in horizontal longitudinal alignment with respect to the retort, and those of
- 10 15 the other shape terminating below such aligned portions, and means for reciprocating the bars of one shape relatively to those of the other.
- 15 20 3. A furnace as in claim 2 and wherein are cap plates extending across from the tops of the retort sides to the top portions of the grate bars of the first shape and interlocked therewith.
- 25 30 35 40 4. In a furnace having a central fuel retort and a pair of oppositely inclined grates one along each of the lateral sides of the retort, the retort discharging laterally over such sides upon such grates, each grate composed of inclined grate bars having stepped fuel supporting top sides, and loosely interfitting to afford numerous narrow and non-sifting air passages delivering into the fuel bed, twyer members resting on the retort sides, and a series of separate removable cap pieces overlying the tops of the twyer members and alternate grate bars and having underneath interlocking engagement with the top edges of both the twyer members and such alternate grate bars, and means for reciprocating the remaining grate bars.

In witness whereof, we have affixed our signatures hereto.

ERNEST B. PRIEBE.
DANIEL P. MINER.
